UNITED STATES PATENT OFFICE.

AUGUST W. CORDES, OF NEW YORK, N. Y.

VENDING-MACHINE.

SPECIFICATION forming part of Letters Patent No. 792,650, dated June 20, 1905.

Application filed June 28, 1904. Serial No. 214,460.

To all whom it may concern:

Be it known that I, AUGUST W. CORDES, a citizen of the United States, residing at New York city, Manhattan, county and State of New York, have invented certain new and useful Improvements in Vending-Machines, of which the following is a specification.

This invention relates to a vending-machine which is so constructed that the magazine containing the goods to be sold is separable from the frame containing the coin-controlled delivery mechanism or vending device proper. In this way a larger supply of goods is rendered available than can be held by the frame containing the delivery mechanism, and as the magazine occupies the space generally taken up by the stand a considerable saving of space is effected.

In the accompanying drawings, Figure 1 is a vertical section of my improved vending-machine; Fig. 2, a front elevation, partly broken away at the upper portion thereof; Fig. 3, a vertical section on line 3 3, Fig. 1; Fig. 4, a horizontal section on line 4 4, Fig. 1; Fig. 5, a similar section on line 5 5, Fig. 1; and Fig. 6, a detail of the plunger-clamp.

The letter *a* represents a magazine mounted on a base-plate *a'*, which is adapted to be supported by the floor of the vending-station. At an elevation above base-plate *a'* there projects from the magazine *a* a bracket *a''*, upon which the frame *b* of the vending-machine proper is adapted to be supported. The magazine *a* constitutes a storage-chamber for the goods to be sold, while the frame *b* contains the coin-released delivery device for passing such goods to the consumer. The frame *b* is removably coupled to the magazine *a*, and means are provided for establishing communication between the frame and magazine when the parts are connected. Thus it will be seen that an extensive stock may be maintained at the vending-stations, while at the same time the vending-machines proper may be freely removed and examined without necessitating the simultaneous removal of the magazine or the goods contained therein.

Communication may be established between the parts *a* and *b* by means of an opening *a''* in the front wall *a'* of the magazine, which is adapted to register with a corresponding

opening *c* of a slide *c*, that forms the back of frame *b*. The slide *c* is guided within corresponding grooves of frame *b* and constitutes the means for locking such frame to bracket *a''*. To this effect the slide terminates at its bottom in a pair of lugs *c'*, Fig. 3, adapted to be projected through corresponding perforations of the raised foot *b'* of frame *b*. These lugs engage fixed stops *a''*, secured to bracket *a''* in front of slide *c*, and thus connect the back of the frame to the back of the bracket. In front of stops *a''* the bracket *a''* carries a hook *a'''*, that enters an eye *b''*, depending from foot *b'*. To attach frame *b* to magazine *a*, the former is slid rearward upon bracket *a''*, whereby hook *a'''* will be projected through eye *b''*. Then the slide *c* is lowered to engage stops *a''*, and, finally, the slide is locked in position in manner hereinafter described.

Within the magazine *a* is fitted a plunger *d*, having an inclined top platen *d'* that slants downward from the rear toward the front and upon which the cylindrical or other goods *A* are supported. The plunger *d* is provided with a horizontal partition *d''*, a rear hand-hole *d'''*, and a pair of vertical partitions *d'''* beneath partition *d''*. The partitions *d'''* thus form a central compartment within the lower end of plunger *d*, which is adapted for the reception of the upper end of a coiled spring *e*, mounted within magazine *a* upon base-plate *a'*. The spring *e* will raise the plunger *d* and cause the goods *A* to be crowded against an inclined guide-plate *f*, arranged in magazine *a* above the plunger and slanting upward from the rear to the front, so as to diverge from top plate *d'* of plunger *d*. By the joint action of the plunger and guide-plate the goods will thus be pushed from the magazine *a* into a pocket *b''* of frame *b*, which communicates with the magazine through openings *a'' c'*. To prevent an excessive discharge and place the goods into parallelism, the guide-plate *f* is provided with a forward extension *f'*, that enters pocket *b''* through openings *a'' c'*. This extension is first bent upward to prevent bridging, then forward, and then downward, as shown, and thus constitutes a deflector against which the goods are forced by the action of plunger *d*. Below deflector *f* there is pivoted to frame *b* at *g* an oscillating shelf *g*, supported at its for-

ward end upon a bulged oscillating agitator h , having a projection h' and pivoted at h^2 . The agitator h is provided at its forward end with a number of fingers h^3 , that enter corresponding perforations in the periphery of a delivery-drum i , turning on shaft i' . This drum has a peripheral notch i^2 for grasping the goods A and delivering the same from pocket b^5 to the operator. The drum i may be oscillated by a handle i^4 after being released by means of a suitable mechanism, which does not form part of the present invention. The oscillation of drum i causes a simultaneous oscillation of agitator h , which in turn by projection h' will vibrate shelf g . In this way the goods A delivered from magazine a into pocket b^5 will be shaken up sufficiently to prevent clogging of the machine and adhesion between the different pieces of goods.

20 Across the upper rear end of pocket b^5 extends a transverse rail j , that constitutes the support for the upper bent end c^3 of slide c . From the rail j projects upwardly a perforated lug j' , adapted to engage the perforated 25 rear end of a cover k and the perforated front end of a cover l . The cover k is hinged at k' to the front wall b^6 of pocket b^5 , while the cover l is hinged at l' to the back a^7 of magazine a . If the parts a and b have been connected by 30 the descent of slide c , as previously described, the covers k and l are closed and secured to rail j by a padlock m , which thus also serves to lock slide c in its downward position.

To charge the magazine a , its back a^7 is 35 made removable and provided with lower hooks a^8 and an upper flange a^9 . The hooks a^8 engage corresponding projections a^{10} of base-plate a' , while the flange a^9 projects beneath a pin a^{11} of magazine a . In charging the 40 magazine the back a^7 is removed, and the plunger d is depressed by passing a hand into opening d^3 . The plunger is now locked in its lowered position by means of a suitable clamp n , that is pivoted to the plunger at n' 45 and bears against one of a pair of upright guide-rails a^{12} of plunger d , (full lines, Fig. 6.) After the magazine is charged the clamp n is swung up (dotted lines, Fig. 6) to release rail a^{12} , the back is secured in position, and the 50 cover l is closed and locked to rail j .

It will be seen that by the use of a single lock m the frame b and magazine a are closed and the frame is locked to the shelf.

To uncouple the frame, the lock m is opened, 55 the lids k l are thrown up, and the slide c is raised to become disengaged from stops a^5 . The frame being thus disconnected may now be removed from the shelf, while the magazine remains undisturbed at the selling-sta- 60 tion. To prevent the goods from falling out of the magazine through opening a^3 after the frame b has been detached, the plunger is lowered or the magazine may be provided with a gate o , adapted to be projected across 65 the opening.

What I claim is—

1. In a vending-machine, a frame having a delivery mechanism, combined with a magazine which is detachable from said frame, substantially as specified.

2. In a vending-machine, a frame having a delivery mechanism, combined with a detachable magazine, and means for locking the magazine to said frame, substantially as specified.

75 3. In a vending-machine, a frame having a delivery mechanism and an open back, combined with a detachable magazine having an open front, and means for locking the magazine to said frame, substantially as specified.

80 4. In a vending-machine, a magazine having a spring-plunger, an open front and a bracket, combined with a frame adapted to be supported upon said bracket and having a delivery mechanism and an open back, and means for locking the frame to the magazine, substantially as specified.

85 5. In a vending-machine, a frame having a delivery mechanism, combined with a detachable magazine, a plunger having an inclined platen, and a reversely-inclined guide-plate above the platen, substantially as specified.

90 6. In a vending-machine, a frame having a delivery mechanism and a pocket, combined with a detachable magazine provided with a guide-plate, which is turned downward at its front and projects into said pocket, substantially as specified.

95 7. In a vending-machine, a frame provided with a delivery mechanism and with a rear slide having an opening, combined with a detachable magazine having a bracket adapted to support the frame, means for locking the slide to the bracket, and a front wall having an opening which is adapted to register with the slide-opening, substantially as specified.

100 8. In a vending-machine, a frame having a delivery-drum, an agitator engaging the same, and an oscillating shelf engaging the agitator, combined with a detachable magazine adapted to be secured to the frame, substantially as specified.

105 9. In a vending-machine a frame having a delivery mechanism, combined with a detachable magazine having a removable back, and means for locking said back to the magazine, substantially as specified.

110 10. In a vending-machine, a frame having a vending mechanism, a transverse rail, a slide and a hinged lid, combined with a detachable magazine, having a removable back and a hinged lid, and with means for locking the slide and lids to the rail, substantially as specified.

115 Signed by me at New York city, (Manhattan,) New York, this 27th day of June, 1904.

AUGUST W. CORDES.
